(57) CLAIM

The ornamental design for a water delivery system for trees and shrubs, as shown and described.

DESCRIPTION

FIG. 1 is a perspective view of a water delivery system for trees and shrubs embodying my invention;

FIG. 2 is a top plan view thereof;

FIG. 3 is a front elevational view thereof;

FIG. 4 is a bottom plan view thereof;

FIG. 5 is a right end elevational view thereof; and,

FIG. 6 is a left end elevational view thereof.

The broken lines are for illustrative purposes only and are not part of the claimed design.
